CLAIM

The ornamental design for a translucent-top light table,
as shown and described.

DESCRIPTION

FIG. 1 is a top, front and right side perspective view of
a translucent-top light table embodying our new design;
FIG. 2 is a front elevational view thereof, the rear elevational
view being a mirror image;
FIG. 3 is a left side elevational view thereof, the right
side elevational view being a mirror image;
FIG. 4 is a top plan view thereof; and,
FIG. 5 is a bottom plan view thereof.

FIG. 1

FIG. 2

FIG. 3

FIG. 4

FIG. 5
